UNITED STATES PATENT OFFICE.

MARSHAL HENSON, OF DOE RUN, MISSOURI, ASSIGNOR OF ONE-THIRD TO ULYSSUS HAWK, OF DOE RUN, MISSOURI.

ORE-FEEDING MECHANISM.

No. 873,748.

Specification of Letters Patent.

Patented Dec. 17, 1907.

Application filed February 27, 1907. Serial No. 359,631.

To all whom it may concern:

Be it known that I, MARSHAL HENSON, a citizen of the United States, residing at Doe Run, in the county of St. Francois and State 5 of Missouri, have invented a new and useful Ore-Feeding Mechanism, of which the following is a specification.

The principal object of the present invention is to provide simple, novel and effective 10 means for feeding crushed ore, rock, and the like to belt conveyers or other suitable mechanisms. In every feeder, with which I am acquainted, the material clogs the same, necessitating the services of a workman to 15 loosen said material, and resulting in an intermittent flow of the same to the belt. Experience has demonstrated that the mechanism herein set forth will not become so clogged.

20 A further and important object is to provide mechanism, whereby the flow may be readily altered, as desired, and still another object is to provide means, whereby the feeding mechanism can at any time be thrown 25 into and out of operation.

The preferred embodiment of the invention is disclosed in the accompanying drawings, wherein:—

Figure 1 is a side elevation of the same. 30 Fig. 2 is a cross sectional view therethrough. Fig. 3 is a vertical sectional view at right angles to Fig. 2. Fig. 4 is a plan view of the carrier table. Fig. 5 is a plan view of the belt tightener. Fig. 6 is a detail sectional 35 view on the line 6—6 of Fig. 1.

Similar reference numerals designate corresponding parts in all the figures of the drawings.

In the embodiment illustrated, a suitable 40 supporting frame is employed, comprising sills 7, carrying stringers 8, on which are mounted standards 9. These standards support upper beams 10. It is to be understood that any suitable sort of frame may be employed. Operating in the lower portion of 45 this frame is a conveyer belt 11 that passes about a roller 12 suitably journaled in the stringers 8. A yoke 13 extends over the conveyer belt 11, and has depending legs 14 fixed 50 to the stringers 8. This yoke supports a central upright journal box 15 having a lining 16 of Babbitt metal, which metal also extends over the upper end of the box, as shown at 55 17. An upright gudgeon 18 is journaled in the box 15, and has a head 19 that is rota-

60 tably mounted on the portion 17 of the Babbitt metal. From this head extends an upright stem 20, the upper end of which is threaded.

A gear wheel 21 of comparatively great diameter, has a hub 22 located on the stem 20, and resting on the head 19. This gear wheel is furthermore provided on its upper side with a series of lugs 23. A rotatable carrier table 24 has a central opening that receives 65 the upper portion of the stem 20, said table resting on the hub 22 and the lugs 23. A nut 25, threaded on the upper end of the stem, serves to clamp the table and gear wheel together and against relative rotation. 70 It will thus be seen that upon the rotation of the gear wheel, the table will be rotated, said table being in the form of a disk, and its upper face 26 inclining downwardly from the 75 central portion to the edges.

For the purpose of rotating the gear wheel 21, and consequently the table 24, the following mechanism is preferably employed. A roller 27 has gudgeons 28 journaled in boxes 29 fixed to the under sides of the 80 stringers 8, said roller being in frictional engagement with the conveyer belt 11. One of the gudgeons 28 is provided with a beveled gear 30 meshing with a corresponding gear 31 that is fixed to the lower end of an 85 upright countershaft 32 journaled in the boxes 33 of a bracket 34 fastened to one of the legs 14 of the supporting yoke 13. On the upper end of the countershaft 32 is a pinion 35, which is in mesh with the gear wheel 90 21. The shaft 32 can be raised and lowered by means of a lever 36 fulcrumed between its ends and having a yoke 37 engaging in the notches 38 of a sleeve 39 located on the shaft 32, between collars 40 fixed to said shaft. A 95 holding device 41 serves to maintain the lever 36 in either of two positions. It will be evident that by operating this lever, the shaft can be raised and lowered, thus carrying the beveled gear 31 into and out of mesh 100 with the gear 30. A belt tightener for insuring frictional engagement between the belt 11 and the roller 27 is also provided. This belt tightener consists of a rock shaft 42 journaled in the stringers 8, and having a lever handle 43 at one end that cooperates with the holding bracket 44. The rock shaft 42 between the stringers 8 carries a pair of crank arms 45 that are in the form of loops. These loops engage in slots 46 formed in the 110

free ends of swinging arms 47 that carry a roller 48. The roller is located between the stretches of the belt 11 and in close proximity to the roller 27. It will thus be evident that if the lever 43 is swung in one direction, the roller 48 will force the belt 11 into frictional engagement with the roller 27, and consequently said roller 27 will be revolved. If therefore the gears 30 and 31 are in mesh, the countershaft 32 will be rotated, and as a consequence, the gear wheel 21 and table 19 will be revolved.

The carrier table above described, is surrounded by an upright circular stationary wall 49 supported by brackets 50, and this wall at one side is connected to one of said brackets through the medium of a downwardly inclined chute 51 that delivers to the upper stretch of the belt 11. The wall at one side of its juncture with the chute 51 is provided with a guideway 52, and in the same, is slidably mounted a deflector blade or gate 53 that is movable over the upper face 26 of the table, toward and from the axis of rotation of said table. The gate can be held in any desired position by means of a set screw 54 or other suitable device.

Supported on the upper beams 10 of the frame is a hopper 55, and extending from this hopper is a spout 56 composed of suitable material, such as angle iron and sheet metal, said spout being pivotally mounted at its upper end, as shown at 57. The open discharge mouth of the spout is covered by a swinging closure 58 pivoted to said spout, as shown at 59, and having a link 60 pivoted to one of its sides. The link 60 has notches 61 arranged to receive a lug 62 carried by the spout. Thus the closure may be locked in any position desired with respect to the spout and the mouth, and the size of the mouth can consequently be varied to suit the desired amount of feed. The spout has its delivery mouth located over the table and directly in rear of the deflector blade or gate 53, and the table is provided with a central upstanding boss 63 surrounding the nut 25, and carrying a collar 64 that is tightly fitted therein. This collar is provided with upstanding teeth 66, upon which operates a depending lug 67 carried by the lower portion of the spout.

The operation of the structure is substantially as follows: As the table is rotated through the medium of the mechanism above described, the teeth moving beneath the lug 67 will cause the spout to periodically raise, and then permit it to fall. The result is that the material placed in the hopper will gravitate down the spout and the operation thereof will prevent such material clogging therein. The material deposited on the table will be carried around by the same until it is deposited in the chute 51 either by gravitating down the inclined upper face of said

table or by being moved from the table by the deflector. The amount deposited in the chute can be readily varied by adjusting the blade or gate 53, as will be evident by reference to Fig. 4. The material, falling into the chute 51, will gravitate down the same and be deposited on the upper stretch of the belt. Experience with this machine has demonstrated that it is entirely effective for the purpose desired. It will not choke up, its feed can be varied as found desirable or necessary, and the mechanism can be quickly thrown out of operation by moving the belt tightener or raising the countershaft in the manner already described.

From the foregoing, it is thought that the construction, operation, and many advantages of the herein described invention, will be apparent to those skilled in the art, without further description, and it will be understood that various changes in the size, shape, proportion, and minor details of construction, may be resorted to without departing from the spirit or sacrificing any of the advantages of the invention.

Having thus fully described my invention, what I claim as new, and desire to secure by Letters Patent, is:—

1. In feeding mechanism of the character set forth, the combination with a downwardly and outwardly inclined table having a substantially upright axis of rotation, of a circular series of upstanding teeth carried by the central highest portion of the table, a vertically movable spout located above the table and engaged and operated by the teeth, and means for rotating the table.

2. In feeding mechanism of the character set forth, the combination with a table revolute on its substantially upright axis and having a central boss, of a collar fitted in the boss and having upstanding teeth on its upper edge, a spout delivering to the table and having a portion engaged and operated by the teeth, and means for rotating the table.

3. In feeding mechanism of the character set forth, the combination with a movable delivery spout having an open mouth, of a swinging closure pivoted on the spout, a link pivoted to one, means carried by the other for securing the link in different positions thereon, a rotatable table carrier, and means mounted on the table for moving the spout.

4. In feeding mechanism of the character set forth, the combination with a movable delivery spout having an open mouth, of a swinging closure pivoted on the spout, a link pivoted to the closure and having notches, a projection on the spout that engages in the different notches to hold the closure at different positions, a movable carrier table, and means mounted on the table for moving the spout.

5. In feeding mechanism of the character set forth, the combination with a rotatable

carrier table, of an annular wall surrounding the same, a chute extending from the wall and located at one side of the table, a hopper supported above the table, a pivoted chute 5 extending from the hopper and delivering on to the table, said chute having an open mouth, a closure for the mouth pivoted on the chute, means for holding the closure in different positions thereon, and a circular series of upstanding teeth carried by the table 10 and rotatable therewith, said teeth successively engaging the hopper to swing the same.

6. In feeding mechanism of the character set forth, the combination with a rotatable 15 carrier table, of a stationary wall extending around the table and carrying a guide-way, and a reciprocatory deflecting blade slidably mounted in the guide-way and extending 20 over the table, said blade being movable endwise so that its inner end will be located at different distances from the axis of rotation of the table.

7. In feeding mechanism of the character set forth, the combination with a conveyer 25 belt, of a rotatable table located thereover, a downwardly inclined chute extending from one side of the table and delivering on to the belt, a hopper, a movable spout extending 30 from the hopper and delivering on to the table, means carried by the table for operating the hopper, and a deflecting blade disposed at the rear side of the chute and movable to positions over the carrier table at different distances from its axis of rotation.

8. In feeding mechanism of the character set forth, the combination with a supporting 40 frame, of a journal box thereon, a gudgeon journaled in the box, said gudgeon having a head at its upper end and a stem that projects above the head, a gear wheel mounted on the stem and supported by the head, a rotatable table mounted on the stem and supported by the wheel, means engaging the stem and table to clamp the latter to the wheel, and means engaging the wheel to rotate the same and thereby the table.

9. In feeding mechanism of the character set forth, the combination with a supporting 50 frame, of a journal box thereon having a bearing a gudgeon having a step bearing in the box, said gudgeon having a head at its upper end and a stem that projects above the head, a gear wheel mounted on the stem and supported by the head, a rotatable table mounted on the stem and supported by the wheel, said table having an upstanding boss, means located within the boss and engaging the stem and table to clamp the latter to the wheel, means engaging the wheel to rotate the same and thereby the table, feeding mechanism located over the table, and means carried by the boss for operating the feeding mechanism.

65 10. In feeding mechanism of the character

set forth, the combination with a supporting frame, of a journal box thereon, a gudgeon journaled in the box and having a head, an upright stem projecting from the head, a gear wheel having a hub mounted on the 70 stem, upstanding lugs carried by the wheel, a carrier table having a central portion that receives the stem, said table resting on the hub of the wheel and on the lugs, a movable delivery spout located over the table, and a circular series of upstanding teeth carried by the table and surrounding the upper portion of the stem, said teeth operating on the delivery spout.

11. In feeding mechanism of the character 80 set forth, the combination with a supporting frame, of a conveyer belt associated therewith, a downwardly inclined chute delivering to the belt, a rotary carrier table, means located over the carrier table for deflecting the 85 material from the same to the chute, a movable feed spout delivering to the table, and means operated by the table for moving the spout.

12. In feeding mechanism of the character 90 set forth, the combination with a supporting frame, of a conveyer belt operating therein, a rotatable carrier table located over the belt, a wheel surrounding the table, an inclined chute delivering from the table to the belt, 95 a deflector located over the table for deflecting material therefrom into the chute, a delivery spout located over the table and delivering the material on to the same in rear of the deflector, means operated by the table 100 for moving the spout, and means operated by the belt for rotating the table, said means including mechanism for stopping the table.

13. In feeding mechanism of the character set forth, the combination with a supporting 105 frame, of a conveyer belt operating therein, a rotatable carrier table located over the belt, a wheel surrounding the table, an inclined chute delivering from the table to the belt, a deflector located over the table for deflecting material therefrom into the chute, a delivery spout located over the table and delivering the material on to the same in rear of the deflector, means operated by the table 110 for moving the spout, and means operated by the belt for rotating the table, said means comprising a roller associated with the belt, a belt tightener for moving said belt into frictional engagement with the roller, gearing connecting the roller and the table, including a clutch, and means for operating the clutch.

In testimony, that I claim the foregoing as my own, I have hereto affixed my signature in the presence of two witnesses.

MARSHAL HENSON.
